REES C. MORGAN AND JOHN F. PELLY, OF BETHLEHEM, PENNSYLVANIA, ASSIGNORS
TO BETHLEHEM STEEL COMPANY, OF BETHLEHEM, PENNSYLVANIA, A CORPORA-
TION OF PENNSYLVANIA.

METHOD OF ASSEMBLING TUBES AND LINERS IN GUN MANUFACTURE.

Application filed January 11, 1922. Serial No. 528,573.

To all whom it may concern:

Be it known that we, REES C. MORGAN and JOHN F. PELLY, citizens of the United States, and residing at Bethlehem, Lehigh County, State of Pennsylvania, respectively, have invented certain new and useful Improvements in Methods of Assembling Tubes and Liners in Gun Manufacture, of which the following is a specification.

10 This invention relates to methods of assembling liners and tubes of guns of large caliber.

It is a practically universal practice in gun manufacture to provide the liner with one or more forwardly facing annular shoulders which are designed to abut against corresponding rearwardly facing annular shoulders formed on the inside of the tube. These shoulders are intended to prevent the liner 20 from creeping toward the muzzle of the gun in service, due to the "mandrelling-out" effect of the projectiles passing through the bore at high speeds, and to the effect of the powder pressure. In the shrinkage method 25 of assembling the tube and liner the latter is usually placed in a vertical position and either cooled internally by water jets or kept at ordinary room or shop temperature, while the tube is heated and expanded so that the

30 diameter of its bore is greater than the outer diameter of the liner; after which the tube is lowered over the liner and cooled, when it frictionally grips the liner with great force, in a well known manner. It is 35 essential that the one or more shoulders of the liner be seated against the corresponding shoulders of the tube when the assembly is complete, otherwise the liner will creep forward in service, which is objectionable for a 40 number of reasons.

Heretofore it has been very difficult to assemble the tube and liner in such manner that the corresponding shoulder or shoulders are properly seated, largely due to the 45 fact that the hot tube on being dropped around the cool liner causes the latter to expand and contact with the tube at a number of points along its length, and very often toward the muzzle end of the gun, before 50 contact is made at the breech end. Also, as the muzzle end of a tube is of less thickness it cools more quickly and tends to grip the liner first. As the tube contracts longitudinally, as well as diametrically upon cooling,

it is obvious that if it has first gripped the 55 liner in front of a shoulder, that as it contracts longitudinally the shoulder of the tube will recede from the shoulder of the liner, to cause an undesirable gap between 60 the shoulders. If the tube were to first grip 65 the liner in rear of the forwardly facing shoulder of the latter, obviously the shoulders would be drawn together as the tube cools, but this practically never takes place because of the relatively great thickness of 70 the tube at the breech end where it may comprise several concentric cylinders, as compared with its thickness at the muzzle, the heavier breech end being much slower in cooling.

Furthermore, as a direct result of the frictional gripping of tube and liner at a number of points as the tube cools, the liner is 75 forceably longitudinally contracted by the heavier cooling and longitudinally contracting tube and the resulting gun has a liner which is not only under an initial longitudinal compressive stress, which is 80 very undesirable, but in which the "compression," or the actual shortening of the diameter of the bore of the liner may vary 85 widely from the theoretical compression desired.

It is the object of the present invention to provide a method of assembling tubes and 90 liners by shrinkage whereby the corresponding shoulders of tube and liner are firmly and positively seated and longitudinal shortening of the liner prevented so that the liner of the resulting gun is not under initial 95 longitudinal compression; and in which the actual compression realized closely approximates the desired theoretical compression.

The method will be described below, and 100 an apparatus for carrying it out is illustrated in the accompanying drawings in which:

Figure 1 is a longitudinal sectional view through an assembled tube and liner, showing the apparatus in operative position; and 105

Figure 2 is an enlarged partial section through a portion of the apparatus.

In application, Serial No. 528,575, filed January 11, 1922, is described and claimed an apparatus for holding a liner against 110 longitudinal contraction as it is assembled with a tube, and in Figure 1 of the drawings of the present application we have illus-

trated this apparatus combined with additional features for performing the new steps of the present process. It will be understood, however, that these new steps of the present method may be carried out entirely independently of this liner holding apparatus and that various different devices may be satisfactorily utilized.

The apparatus described and claimed in the application above mentioned comprises essentially a steel shaft 10 which extends through the bore of the liner, being held centrally therein by annular spacing members 11. The upper end of this bar 10 has connected thereto a plug 12, which has screw threaded engagement with the muzzle end of the liner itself, and the breech end of the bar 10 is connected or secured to a power device preferably hydraulic, indicated at 13. Swinging arms 14 having hooked ends 15 are also secured to the power mechanism 13, which is adapted when actuated, to effect relative movement between the bar 10 and the arms 14, drawing the tube rearwardly and moving the liner forwardly. Because of the engaging annular shoulders of the tube and liner, indicated at 16, the liner is held against longitudinal contraction between the offset 16 and its muzzle end, thereby insuring, when the assembly has been completed, a gun in which the liner is under no initial longitudinal compression.

In order to insure that the tube and liner shall first engage at the breech or first shoulder of each, means is provided for heating the liner at this section sufficiently to cause an expansion thereof to such an extent that it will without fail be the first section to engage the corresponding section of the tube as the latter gradually contracts while cooling. It is not necessary to heat the liner to a high temperature to bring about this result, and we therefore preferably employ hot water or steam as a heating medium. On the shaft 10 are positioned rings 19 and 20, clearly illustrated in section in Figure 2, these rings being provided with packing strips. The uppermost packing strips are designed to permit a slight leakage of fluid around them and the plug 12 is provided with a vent 12' to allow the escape of air. Conduits are formed in the rear portion of the column 10 for the passage of fluid, a steam or hot water inlet conduit 21 being indicated at 21 and an outlet conduit at 22. To the outer ends of these conduits may be connected flexible fluid conduits for conducting the heated fluid to the conduit 21, and away from the outlet of the conduit 22. By these means steam or hot water may be continually circulated in the annular space around shaft 10 and between the rings 19 and 20, thereby heating this section of the liner and causing its expansion in the desired manner.

In carrying out the method the plug 12 is first screwed into prepared threads in the muzzle end of the liner and the liner placed around vertical shaft 10, being supported only at its muzzle end. The heated tube is then lowered into position over the liner, with its entire weight resting on the shoulders of the liner. Steam is then introduced into the annular space between rings 19 and 20 and the flow of steam is kept up until the liner has been heated sufficiently to give a sufficient diametrical expansion to insure that the expanded section will be the first section to contact with the cooling and contracting tube. Leakage of steam around the upper rings 20 causes the heating and expanding of a section of the liner above this ring and, due to the rising steam, this expansion slowly progresses upwardly. When the steam has been shut off the hydraulic power mechanism is operated to exert an upward force at the muzzle of the liner and a downward force on the tube to positively prevent the longitudinal contraction of the tube or to slightly stretch the same, if found desirable. Preferably the power is applied in stages, being increased from time to time during the cooling of the tube.

The heat from the internal heating plant and the heat passing to the liner by conduction after it has engaged the hot tube is gradually transmitted in both directions along the liner, causing the successive expansion of sections and gradual gripping of liner and tube throughout their lengths. The gradual heating of the liner also causes its gradual extension in both directions. As a result of this method of assembling the shoulders of the tube and liner are not only correctly seated but longitudinal compressive stresses in the liner of the finished gun are practically avoided.

The apparatus may be modified in various ways as will be obvious to those skilled in the art. It is simple, inexpensive to construct and operate and thoroughly efficient, being effective in causing the liner and tube to grip primarily at any section selected and thereby enabling the operator in the shrink pit to be assured that in the assembling operation the various shoulders of the tube and liner are properly seated and that objectionable longitudinal compressive stresses will not be present.

Having thus described the invention what we claim as new and desire to secure by Letters Patent is:

1. The method of assembling a tube and liner by shrinking, consisting in expanding the tube by heat, placing the tube over the liner, and expanding a section of the liner by heat.

2. The method of assembling a tube which diminishes in thickness from one end to the other and a liner by shrinking, con-

sisting in expanding the tube by heat, in placing the tube over the liner, and in expanding the liner by heat to secure progressive contact thereof with the tube from a 5 region near the thick end toward the thin end while at the same time allowing the tube to cool.

3. A method of assembling the tube and liner of a built-up gun having cooperating 10 shoulders near the breech end, consisting in expanding the tube by heat, in placing the tube around the liner, and in expanding a section of the liner at, or in the region of, the shoulders while the tube is cooling.

15 4. A method of assembling a tube and liner, said tube being thicker at one end than at the other, consisting in expanding the tube by heat, in placing the tube around the liner, and in expanding a section of the 20 liner in the vicinity of the thick end of the tube while the latter is cooling.

25 5. A method of assembling a tube and liner, said tube being thicker at one end than at the other, consisting in expanding the tube by heat, in placing the tube around the liner, and in expanding a section of the 30 liner in the vicinity of the thick end of the tube by applying heat internally of the liner while at the same time allowing the tube to cool.

35 6. A method of assembling a tube and liner having shoulders to be seated consisting in expanding by heat the tube along its entire length, placing the expanded tube over the liner, expanding a limited section of the liner by applying steam to the interior of said section of the liner, and cooling the tube to cause it to shrink and grip the liner, throughout the length thereof, but 40 first at the previously expanded section of the liner.

7. A method of assembling a tube and a liner having shoulders to be seated, consisting in expanding the tube by heat through-

out its length, in placing the expanded tube 45 over the liner with the shoulders in contact, in expanding the liner diametrically at the region of a shoulder thereof near one end to secure contact of the tube and liner first at that region while at the same time allowing 50 the tube to cool.

8. A method of assembling the tube and the liner of a built-up gun, the tube having a plurality of interior shoulders facing the breech end and the liner having a plurality 55 of shoulders facing the muzzle end, in expanding the tube by heat throughout its length, in placing the tube over the liner with at least the shoulder near the breech end in contact with the corresponding liner 60 shoulder, and in expanding a section of the liner in the vicinity of the shoulders nearest the breech end to secure contact of the liner with the tube first in that region and then in progressively expanding the liner 65 by heat to secure progressive contact thereof with the tube from said region toward the muzzle end while at the same time allowing the tube to cool.

9. The method of assembling a tube and 70 liner, consisting in expanding the tube by heat, placing the tube over the liner, expanding a section of the liner by heat, stretching or elongating said liner and shrinking the tube on the liner while the 75 latter is in an extended condition.

10. The method of assembling built-up guns, consisting in heating and expanding a tube, placing the tube over a liner, expanding a section of the liner by heat, 80 shrinking said tube upon the liner, and positively preventing longitudinal contraction of said liner.

In testimony whereof we hereunto affix our signatures.

REES C. MORGAN.
JOHN F. PELLY.
